UNITED STATES PATENT OFFICE.

CHARLES L. LINCOLN, OF NEW YORK, N. Y.

SANDING DEVICE FOR AUTOMOBILES.

1,112,301.

Specification of Letters Patent. Patented Sept. 29, 1914.

Application filed November 14, 1913. Serial No. 800,986.

To all whom it may concern:

Be it known that I, CHARLES L. LINCOLN, a citizen of the United States, and a resident of the city of New York, borough of Brooklyn, in the county of Kings and State of New York, have invented a new and Improved Sanding Device for Automobiles, of which the following is a full, clear, and exact description.

10 The object of the invention is to provide a new and improved sanding device for automobiles and similar vehicles to discharge fine gravel, dry, coarse sand or a similar dry, non-packing material onto a roadway immediately in front of the bottom portion of the tires of the rear or drive wheels to prevent the vehicle from skidding on a slippery roadway.

In order to accomplish the desired result 20 use is made of a container adapted to contain a dry, non-packing material, such as fine gravel, coarse sand and the like, a discharge pipe extending from the said container in a rearward direction, a sleeve 25 mounted to slide on the rear end of the discharge pipe and terminating in a nozzle normally closed by a valve, manually-controlled means for imparting a sliding motion to the said sleeve, and automatic means 30 for automatically opening and closing the said valve on imparting a sliding motion to the said sleeve. Use is also made of means for shiftably and removably securing the container in position on the under side of 35 the running board to allow of conveniently filling the container with fine gravel or other non-packing material.

A practical embodiment of the invention is represented in the accompanying drawings forming a part of this specification, in which similar characters of reference indicate corresponding parts in all the views.

Figure 1 is a side elevation of the sanding device as applied to an automobile and 45 with the bottom of the body shown in section; Fig. 2 is an enlarged sectional side elevation of the same; Fig. 3 is a similar view of a portion of the same and with the nozzle valve in open position; Fig. 4 is a 50 cross section of the same on the line 4-4 of Fig. 2; Fig. 5 is an inverted plan view of the sanding device as applied to the running boards of the automobile; Fig. 6 is a plan view of the container with part broken out; 55 and Fig. 7 is a perspective view, partly

broken out, of the clamp for fastening the container in position on the running board.

A container A is shiftably and removably mounted on the under side of each running board B of an automobile or a 60 similar vehicle, and the said container A is adapted to contain fine gravel or dry, coarse sand or a similar dry non-packing material, to be delivered by the device, presently to be described in detail, onto a roadway 65 immediately in front of the lower portions of the tires of the rear or drive wheels B¹ of the automobile. The container A is open on top and is provided with a hopper-shaped bottom A¹ connected at its lower end 70 with a pipe C extending rearwardly and slightly curved in a rearward and downward direction, as plainly indicated in Figs. 2 and 3.

On the pipe C is mounted to slide a sleeve 75 D terminating at its rear end in a nozzle D¹, preferably flattened in a transverse direction, as plainly indicated in Fig. 5, and the said sleeve D is mounted to slide in a suitable bearing E attached to the under side of 80 the container A. The nozzle D¹ is normally closed by a valve F pivoted at F¹ on the top of the nozzle D¹, and the said valve F is provided with an upwardly-extending arm F² pivotally connected with 85 a rod G extending forwardly and mounted to slide in a bearing H attached to the top of the sleeve D. The rod G is provided with spaced shoulders G¹, G² adapted to engage a stop pin E¹ forming part of bearing or bracket E. It will be noticed that when the sleeve D is in forward position on the pipe C, as shown in Fig. 2, then the valve F is in closed position and the shoulder G¹ is adjacent the stop pin E¹. When 90 the sleeve D is moved rearwardly, as hereinafter more fully described, then the rod G is carried along and its shoulder G² finally moves in engagement with the stop pin E¹ so that on further rearward movement of the sleeve D the rod G exerts a pull 95 on the arm F² to swing the valve F into open position, as shown in Fig. 3.

In order to impart a sliding movement to the sleeve D the following arrangement is 105 made: The sleeve D is pivotally connected at its front end by a forwardly-extending rod or pitman I with a crank pin J¹ on an arm J² secured to a crank shaft J extending transversely and journaled in suitable bear- 110

ings E^2 attached to the under side of the running board B . By reference to Fig. 5 it will be noticed that the rods I of the two sanding devices on the running boards B are connected with the arms J^2 on the same crank shaft J so that when the latter is rocked a simultaneous rearward or forward sliding movement is given to both sleeves D of the two sanding devices. The crank shaft J is provided at or near its middle with a crank arm J^3 pivotally connected by a link K with the lower end of a pedal lever L fulcrumed at L^1 on a bracket E^3 attached to the under side of the bottom B^2 of the body of the automobile, as indicated in Fig. 3. The upper end of the pedal lever L extends through an opening B^3 in the bottom B^2 so that the upper end of the said lever L is within convenient reach of the foot of the chauffeur or other person in charge of the automobile. A spring N is attached at one end to a bracket A^2 formed on a reinforcing plate A^3 held on the under side of the container A , and the other end of the said spring N is attached to the link or pitman I to normally hold the sleeve D in the retracted position shown in Figs. 2 and 5. When the chauffeur imparts a swinging motion to the pedal lever L then a rocking motion is given to the shaft J whereby each of the rods I of the two sanding devices is moved rearwardly to impart a rearward sliding movement to the corresponding sleeve D . The sleeve D in moving rearwardly also moves downwardly so that its nozzle D^1 is in close proximity to the roadway immediately in front of the corresponding rear or drive wheel B^1 of the automobile. When the sleeve D moves into rearmost position the valve F is opened, as previously explained, to allow the gravel or coarse sand to pass out of the nozzle D^1 onto the roadway in front of the rear or drive wheel B^1 . It is understood that during the rearward movement of the sleeve D the spring N is placed under tension, and when the operator releases the pedal lever L then the several parts return to the normal position shown in Figs. 1, 2 and 5.

It will be noticed that the material contained in the container A passes by its own gravity into the pipe C and along the same into the forward end of the sleeve D held closed at the time by the valve F . As the material is in the form of gravel or dry, coarse sand it is evident that it readily passes from the container A through the pipe C into the sleeve D to fill the front end of the latter especially as sufficient vibration is given to the parts mentioned while the vehicle is running to accomplish the desired result, that is, to fill the pipe C and the forward end of the sleeve D with the contents of the container A . When the operator presses the pedal lever L , as previously men-

tioned, the sleeve D is caused to slide rearwardly and the valve F is opened so that the material contained in the sleeve D readily passes out through the nozzle D^1 and down onto the roadway in front of the rear or drive wheel B^1 to prevent the latter from skidding on a slippery roadway. When the operator releases the pressure on the lever L the sleeve D slides forward as previously explained and its rear end is again gradually filled with the material contained in the pipe C owing to the incline of the latter and the vibration given to the pipe C incident to the running of the automobile.

It is understood that fine gravel or coarse sand readily rolls along in the pipe C and the sleeve D without danger of packing in the said pipe or the sleeve, and hence when the sleeve D is pushed rearwardly and the valve F is opened therein the material readily rolls out of the nozzle D^1 down onto the roadway. By using fine gravel or coarse, dry sand a firm adhesion is had between the peripheral face of the rear or drive wheel B^1 and the roadway to prevent the automobile or similar vehicle from skidding on a slippery roadway. It is understood that when the sleeve D is in normal retracted position it is a sufficient distance above the roadway to clear obstructions in the roadway and consequently the parts of the sanding device are not liable to be damaged. When the sleeve D is pushed rearwardly and downwardly its nozzle D^1 is sufficiently close to the roadway to properly scatter the gravel or coarse sand on the roadway immediately in front of the tire of the rear or drive wheel B^1 to insure proper adhesion of the said wheel on the roadway with a view to prevent skidding.

Each container A is preferably mounted to slide transversely on guideways O attached to the under side of the corresponding running board B so that each container can be drawn out partly to permit of conveniently filling the container with fine gravel or coarse, dry sand. The running board B normally covers the open top of the container A , and the container A is normally fastened in place by screw rods P held on the outer ends of the guideways O and engaging the outer side A^4 of the container A . When it is desired to slide the container A outward the nuts P^1 of the screw rods P are unscrewed to unfasten the container A and to allow of drawing the same outward for filling purposes.

The outer side A^4 of each container A is extended at the ends and bottom to act as a protector for the sanding device. It will be noticed that the pipe C , sleeve D , valve F and rods G and I are supported by and move with the container A when the latter is shifted transversely for filling purposes or is entirely removed from the machine.

The rod I has a detachable connection with the pin J¹ to permit of temporarily disengaging the said rod I from the pin J¹ when drawing the container out for filling the same or when removing the sanding device from the automobile. The pedal lever L, link K and crank shaft J may or may not be removed when detaching the container and the parts carried thereby from the machine. The rear of the container is provided with a recess A⁵ for accommodating the pipe C, sleeve D and rod G thus permitting the use of a long container to hold a large quantity of gravel or sand and at the same time support the said pipe C, sleeve D and rod G.

The sanding device shown and described is very simple and durable in construction and composed of comparatively few parts, not liable easily to get out of order. It will also be noticed that the sanding device can be readily applied to automobiles and similar machines as now generally constructed.

Having thus described my invention, I claim as new and desire to secure by Letters Patent:

1. A sanding device for automobiles, comprising a rigid container adapted to contain a dry, non-packing material, a pipe secured to and leading from the said sand box, a sleeve mounted to slide on the end of the said pipe and terminating in a nozzle, and manually controlled means connected with the said sleeve to impart a sliding motion to the same to project the nozzle farther beyond the end of the pipe and into close proximity to the roadway immediately in front of the rear drive wheel of the automobile.

2. A sanding device for automobiles, comprising a container adapted to contain fine gravel, dry, coarse sand or like dry non-packing material, a pipe leading from the said container and inclined downwardly and rearwardly to terminate a distance from the rear or drive wheels of the automobile, a sleeve slideable on the rear portion of the said pipe and terminating in a nozzle, and manually-controlled means for imparting a sliding motion to the sleeve, the latter when in retracted position having its nozzle a safe distance above the roadway and the sleeve when in extended position having its nozzle in close proximity to the roadway immediately in front of the rear drive wheel of the automobile.

3. A sanding device for automobiles, comprising a container adapted to contain fine gravel, dry, coarse sand or like dry non-packing material, a pipe leading from the said container and inclined downwardly and rearwardly to terminate a distance from the rear or drive wheels of the automobile, a sleeve slideable on the rear portion of the said pipe and terminating in a nozzle, a

valve normally closing the said nozzle, means for opening the valve on sliding the sleeve rearward, and manually-controlled means for imparting a rearward and return sliding motion to the said sleeve.

4. A sanding device for automobiles, comprising a container adapted to contain fine gravel, dry, coarse sand or like dry, non-packing material, a pipe leading from the said container and inclined downwardly and rearwardly to terminate a distance from the rear or drive wheels of the automobile, a sleeve slideable on the rear portion of the said pipe and terminating in a nozzle, a valve pivoted on the said nozzle and normally closing the same, a rod connected with the said valve and provided with spaced shoulders, a fixed stop for engagement by the said shoulders to automatically open and close the valve, and manually-controlled means for imparting a sliding movement to the said sleeve.

5. In combination, an automobile having running boards, a container detachably mounted on the under side of each of the said running boards, delivery means adjustable rearwardly with respect to the container for delivering the contents of the said container to the roadway in front of the rear wheels of the automobile, and a controlling device for moving the said delivery means and under the control of the operator.

6. In combination, an automobile, having running boards, a container on the under side of each of the said running boards, delivery means connected with the container for delivering the contents of the said container to the roadway in front of the rear wheels of the automobile, the said delivery means including a pipe fixed on the container, and a sleeve held to slide on the said fixed pipe, the sleeve having a discharge nozzle and a controlling device under the control of the chauffeur and connected with the said sleeve to impart a sliding motion to the sleeve.

7. In a sanding device for automobiles, the combination of transverse guideways on the under side of the running board of the automobile, a container slidably held on the said guideways and depending from the running board, and means for locking the said container in place.

8. A sanding device for automobiles, comprising a support attached to the under side of the running board of the automobile, a container held removable on the said support and depending from the running board, a pipe fixed to and extending rearwardly from the said container, a discharge sleeve mounted to slide on the said pipe and having a discharge spout delivering the contents of the container to the roadway in front of the rear wheels of the automobile, a

rod connected with the said sleeve, and actuating means mounted on the automobile and connected with the said rod.

9. A standing device for automobiles, comprising a support attached to the under side of the running board for the automobile, a container held removable on the said support and depending from the running board, a pipe fixed to and extending rearwardly from the said container, a discharge sleeve mounted to slide on the said pipe and having a discharge spout for delivering the contents of the container to the roadway in front of the rear wheels of the automobile, a rod connected with the said sleeve, and actuating means mounted on the automobile and connected with the said rod, the latter being detachably connected with the said actuating means to allow shifting or removal of the container and the parts carried thereby.

10. A sanding device for automobiles, comprising a support attached to the under side of the running board of the automobile, a container held removable on the said support and depending from the running board, a pipe fixed to and extending rearwardly from the said container, a discharge sleeve mounted to slide on the said pipe and having a discharge spout for delivering the contents of the container to the roadway in front of the rear wheels of the automobile,

a rod connected with the said sleeve, actuating means mounted on the automobile and connected with the said rod, a valve controlling the said spout, a rod connected with the said valve and provided with spaced shoulders, and a fixed stop pin adapted to be engaged by the said shoulders.

11. In an automobile, the combination of a running board having guides, and a sanding device including a container depending from the running board in said guides and held shiftable and removable therefrom.

12. In combination, an automobile having running boards, a container mounted on the under side of each of the running boards, a delivery nozzle adjustable rearwardly with respect to the container for delivering the contents thereof to the roadway in front of the rear wheels of the automobile, an annular controlling device for moving the delivery nozzle and a valve on the nozzle arranged to respectively open and close when the nozzle is moved rearwardly and forwardly.

In testimony whereof I have signed my name to this specification in the presence of two subscribing witnesses.
